UNITED STATES PATENT OFFICE.

WILMER H. YERKES, OF PITTSBURGH, PENNSYLVANIA.

COMBINED RAIL CHAIR, FASTENER, AND TIE.

1,213,326

Specification of Letters Patent. Patented Jan. 23, 1917.

Application filed April 24, 1916. Serial No. 93,102.

To all whom it may concern:

Be it known that I, WILMER H. YERKES, a citizen of the United States, residing at Pittsburgh, in the county of Allegheny and State of Pennsylvania, have invented certain new and useful Improvements in Combined Rail Chairs, Fasteners, and Ties, of which the following is a specification.

This invention relates to a combined rail chair, fastener and tie, more particularly an improvement upon Letters Patent granted to me May 11th, 1909, No. 921,575, and besides possessing the objects and advantages set forth in the Letters Patent referred to its further aim is to provide a combined rail chair, fastener and tie including means to prevent looseness of the track rails when fastened or connected and the said means further compensates for any wear or irregularity in the track rails when coupled together, and the said means further provides a rail chair or connection without the employment of nuts and bolts, at the same time providing for the contraction and expansion of the track rails due to climatic influences.

A further object of the invention is to provide a combined rail chair, fastener and tie having means associated therewith for connecting the rail chairs together to provide a solid metal base for the track rails so as to strengthen a light rail to carry a heavy load and to further strengthen curves down grade.

Further objects of the invention are to provide a combined rail chair, fastener and tie including a fastener of cam like construction which is shifted to fastening position to provide a perfect solid metal fastener for securing the rail within the chair and which prevents lateral as well as vertical movement of the rail. The fastener whether used to connect the abutting ends of a pair of rails or to attach the rail with each tie does away with the employment of bolts, nuts and spikes in laying a rail.

A further object of the invention is to provide a rail chair including a side wall which provides an over-head grip by which, in connection with the fastener, the ends of the track rails are held level and the weight is thrown on the advanced rail in advance of the wheel passing from the delivery end of one rail to the receiving end of the advanced rail, thus saving the receiving end of

the rail from the delivery end of the rail, hence both ends will have the same life and obtain a saving with respect to the entire rail bed of a track. It is the lighter weight which is thrown on the base of the rail 60 chair and the side walls, which provides the over-hanging grip, throwing the weight on the advance rail and also draws the weight to the center, thus tightening the whole force of the grip against the bed and the 65 head of the rail, hence the rail is supported and held in place automatically.

Further objects of the invention are to provide a combined rail chair, fastener and tie which is comparatively simple in its construction and arrangement, strong, durable, efficient and convenient in its use, readily set up, and comparatively inexpensive to manufacture.

With the foregoing and other objects in view the invention consists of the novel construction, combination and arrangement of parts, as hereinafter more specifically described and illustrated in the accompanying drawings, wherein is shown an embodiment 75 of the invention, but it is to be understood that changes, variations and modifications can be resorted to which come within the scope of the claims hereunto appended.

In the drawings wherein like reference 85 characters denote corresponding parts throughout the several views:—Figure 1 is a top plan view illustrating a combined rail chair, fastener and tie in accordance with this invention and showing the adaptation 90 thereof of a pair of track rails. Fig. 2 is a cross-sectional view. Fig. 3 is a perspective view of one of the rail fasteners. Fig. 4 is a perspective view of one of the fish plates. Fig. 5 is a sectional view illustrating the 95 modified form of rail chair employed in connection with the coupling of the rail chairs together to provide a solid metal base for the track rails. Figs. 6 and 7 are views illustrating the modified form of rail 100 chair in connection with the coupling plate.

Referring to the drawings in detail 1 and 2 denote a pair of track rails and each of which includes a head 3, web 4 and base 5. The track rails 1 and 2 oppose each other 105 and supporting the bases 5 of said track rails is a rail chair comprising a base plate 7 and a pair of vertically disposed side walls 8, 9, against which are positioned the longitudinal edges of the bases 5. The side 110

walls 8, 9, project above the bases 5 and each of which has its inner face, near the top thereof, formed with a semi-cylindrical groove 10 providing an inwardly arranged over-hanging hook 11.

Associated with the rail chair and mounted upon the bases 5 of the track rails 1, 2, one at each side of said rails, is a pair of fish plates or splice bars, and each of said fish plates consists of a vertically disposed member 12 and a horizontally disposed member 13, the latter extending at right angles with respect to the base of the former and having its upper face formed with a pair of spaced shoulders 14, 15, upon the longitudinal marginal portion thereof. The vertical member 12 has its outer face, centrally of the top thereof, formed with an outwardly projecting lug 16, having a beveled lower face 16'. The member 12 has a plurality of openings 17 which align with the openings 18 in the webs 4.

When the fish plates are mounted in position they are arranged upon the bases 5 and extend in close proximity to the inner faces of the walls 8 and 9. The fish plates furthermore extend to a point in close proximity to the heads 3 and the members 12 of said plates have their inner faces flanged 30 as at 19, 20, so the said inner faces will be spaced from the webs 4.

When the fish plates are mounted in the position shown in Fig. 2, the openings 17 align with the openings 18 and extending 35 through the alining openings are cylindrical bars 21 which do not project beyond the outer faces of the members 12 of the fish plates.

For maintaining the fish plates or splice 40 bars in position, fastener elements are employed, and each element consists of an angle-shaped member 22, having the horizontal arm 23 thereof of less width than the vertical arm 24 thereof. The horizontal 45 arm 23 terminates in a projection 25 which is crescent-shaped in cross-section and which is adapted to be seated in the groove 10 and over-lapped by a hook 11. The top edge of the arm 24 has a lug 26 at one side of 50 the center thereof.

When the fastener elements are mounted in position they are so arranged against the fish plates that the arms 24 will be seated against the fish plates below the lugs 16 55 and the arms 23 will be positioned upon the members 13 of the fish plates between the shoulders 14, 15, and these latter will prevent longitudinal shifting of the element. The cams 25, when the fastener elements 60 are arranged in the manner as stated, extend in the grooves 10 and are over-lapped by the hooks 11, this arrangement preventing any vertical movement of the cams.

Interposed between the top edges of the 65 arms 24 of the fastener elements and the

lugs 16 are wedges 27 which are driven into position against the lugs 26.

In the form shown in Fig. 5, the fish plates which are referred to by the reference characters 28, 29, are of a construction similar to that shown in Fig. 4 with the exception that the vertical members of the fish plates are not provided with the openings 17. The fastener elements 30 are of a construction similar to the fastener elements shown in Fig. 3. The rail chair which is indicated by the reference character 31 is similar in form to the rail chair shown in Fig. 2 with this exception, that each end of the rail chair has depending therefrom, a channel-shaped member 32, which provides a groove 33. The members 32 are employed in connection with flanged coupling plates 34 for connecting the rail chairs together to form a solid base for the bases 85 of the track rails.

The reference character 35 denotes one end of a tie (the other end not shown) which is formed integral with the base plate of the rail chair and includes angularly disposed webs 36 which are formed integral with the base plate of the rail chair. The webs 36 do not extend through the edges of the chair, so that when the form of chair illustrated in Fig. 5 is employed, the webs 36 constitute a support for the members 32.

The arms 24 of the fastener elements maintain the cylindrical rods 21 in position.

The rail chair however may not be formed integral with the tie body, but may be provided with any suitable means to enable it to be clamped to a wooden tie.

What I claim is:—

1. A combined rail chair, fastener and tie comprising a chair base plate supporting the base of a track rail, opposed walls projecting upwardly from the plate and having over-hanging hooks, fish plates arranged between said walls and adapted to be mounted upon the base of the track rails at opposite sides thereof, fastener elements mounted against said fish plates and having crescent-shape projections seated in said walls and further over-lapped by said hooks whereby the fish plates are maintained in position to hold down the rail, and said fish plates having means engaging the ends of said fastener elements to prevent longitudinal shifting thereof, lugs carried by the fish plates and over-hanging said fastener elements, and wedges interposed between said lugs and said fastener elements.

2. In combination a rail chair for supporting the base of a track rail, fish plates positioned within the chair and adapted to be mounted upon the base of the track rail, fastener elements positioned against the fish plates and extending into the sides of the chair, and means carried by the fish plates and engaging the ends of the fastener ele-

ments to prevent longitudinal movement of said elements, lugs carried by the fish plates and over-hanging said fastener elements, and wedges interposed between the 5 lugs and fastener elements.

- 3. A combined rail chair and fastener comprising a chair plate for supporting the base of the track rails, vertically disposed opposed walls projecting upwardly from 10 said plate and having their inner faces at their upper portions cutaway to provide over-hanging hooks, angle shaped fish plates adapted to be mounted upon the base of the track rail at opposite sides thereof and having 15 the bases thereof positioned against the plane portions of the inner faces of said walls, fastener elements mounted upon said fish plates and having crescent-shaped projections seated in said faces and over-lapped 20 by said hooks whereby the fish plates are maintained in position to hold down the rail, and said fish plates having their bases provided with means near each end engaging the ends of said projections to prevent longitudinal 25 shifting of the fastener elements.

4. A rail chair comprising a base plate connected with a tie, means mounted within the chair for fastening a track rail therein, a channel-shaped member depending from 30 each end of said plate, and means mounted in said members for coupling said chair to

a pair of opposed chairs and providing a support for the base of a track rail.

5. In combination a rail chair for supporting the base of a track rail, fish plates 35 positioned within the chair and adapted to be mounted upon the base of the track rail, fastener elements positioned against the fish plates and extending in the sides of the chair, and means carried by the fish plates 40 and engaging the ends of the fastener elements to prevent longitudinal movement of said elements, lugs carried by the fish plates and over-hanging said fastener elements, and wedges interposed between the lugs and 45 fastener elements, and means engaging the top edge of said fastener elements to arrest vertical movement thereof.

6. A rail chair comprising a base plate connected with a tie, a channel-shaped member depending from each end of said plate, and means mounted in said members for coupling the base plate to the base plates of a pair of opposing chairs to provide a support for the base of a track rail between the 50 ties.

In testimony whereof I affix my signature in presence of two witnesses.

WILMER H. YERKES.
